UNITED STATES PATENT OFFICE.

GILBERT L. CROWELL, JR., OF ARLINGTON, NEW JERSEY, ASSIGNOR TO
DAMON GREENLEAF AND JOSEPH HAYDEN CROSBY, JR., OF JACK-
SONVILLE, FLORIDA.

DESIGN FOR A SPOON, &c.

SPECIFICATION forming part of Design No. 21,601, dated June 7, 1892.

Application filed April 13, 1892. Serial No. 429,071. Term of patent 7 years.

To all whom it may concern:

Be it known that I, GILBERT L. CROWELL, Jr., a citizen of the United States, and a resident of Arlington, in the county of Hudson and State of New Jersey, have invented and produced a new, original, and useful Design for Handles of Spoons and Similar Articles, of which the following is a description, reference being had to the accompanying drawing, 10 which fully illustrates the design as applied to a spoon-handle.

The drawing accompanying this description represents the design as applied to the front of a spoon-handle. The outline of the 15 handle is of spatulate form—that is, its upper end and widest portion is rounded and the sides converge gradually to form the shank of the handle. At the upper end and on the

front side of the handle is the representation A of a wall and of a gateway or passage 20 through the wall. On each side of such passage or gateway is the representation of a tower B. The foreground to this passage or gateway is shown as representing a street or approach to the gateway, such representation 25 of street-approach extending downwardly toward the shank of the handle.

What is claimed as new is—

The design for handles of spoons and similar articles, substantially as shown and described. 30

GILBERT L. CROWELL, JR.
